ADJUSTABLE WIRE LUG

Reynold A. Ohlson, Plainville, Conn., assignor to
 The Trumbull Electric Manufacturing Company,
 Plainville, Conn., a corporation of Connecticut

Application January 29, 1935, Serial No. 3,900

7 Claims. (Cl. 173—259)

My invention relates particularly to terminals for electrical panels, switches, etc. and the main object is to provide an effective electrical connecting device for multiple strand cables of various sizes.

Another object is to provide a terminal that can be mounted in various positions. Another object is to provide a construction that can be used for connection either of the end of a cable or to a point intermediate the ends.

The terminal accordingly is composed of three parts. Two of the parts are in the form of solid blocks having complementary inclined faces with interposed grooves which form the clamping jaws. One block forms the base or stationary jaw member and the other block is mounted so as to slide on the base block. The third part is in the form of a screw or bolt which draws the two blocks together to clamp the cable in the grooves between the blocks.

Fig. 1 is a plan view of a panel with terminals involving my invention.

Fig. 2 is an edge view of the same.

Fig. 3 is a side view of a switch terminal of my invention on a larger scale, the jaws being fully opened.

Fig. 4 is a plan view of the device of Fig. 3 and showing in dot and dash lines two other positions.

Fig. 5 is a side view showing the jaws of Fig. 3 closed.

Figs. 6 and 7 are perspective views of the two blocks.

The blocks 7 and 8 are formed of brass, copper or other suitable metal and preferably drawn together by a bolt or screw 9 and nut 10. For convenience they are usually mounted on a terminal plate 11. The two blocks are provided with complementary inclined faces 12 and 13 through which the screw passes and the similarly complementary inclined faces 14 and 15 in a plane offset from the plane of the faces 12 and 13. Interposed between these pairs of faces are grooves 16 and 17 which with the walls 12 and 15 form a passage for the cable.

The block 8 has an elongated slot 18 which permits the top block to slide on the base block 7. When the blocks are in the position of Fig. 3 the passage 18 is fully open for the insertion of the wire or cable. By tightening the nut 10 the cable is clamped and all ends drawn together and compressed to the most perfect electrical connection possible.

The arrangement of the angular surfaces makes it possible for the blocks to move from the fully

opened position to a practically closed position without any opening through which the strands of wire may escape. It also tends to distort the strands of wire thus making a better and more secure contact.

It will be noted that the lug may be swivelled so that the wires may approach from either side or the end of the terminal or any intermediate angle which, in some cases, is of advantage as shown in Fig. 4.

It will be understood of course that the terminal will usually be mounted on an insulating base such as 20.

In some instances, a series of single pole units are wired at one end with a continuous wire 21. In such instances the lug is adapted to receive a wire which has been stripped of insulation at the required distances or spacings.

In this case of course it will be necessary to remove the top jaws in order to lay the wire in the lower or base jaw grooves 16. The top jaws are then placed in position and clamped down.

The wires 22 at the other side may be inserted endwise and the lugs adjusted at any desired angle.

I claim:

1. An adjustable wire lug including two blocks each having two inclined vertically offset parallel faces with a semi-circular pocket between said faces, the faces of the respective blocks sliding upon each other without rotation to vary the size of the opening formed by the pockets and a clamp screw for connecting the two blocks.

2. An adjustable wire lug including two blocks each having two inclined vertically offset faces with a wire gripping pocket between the faces, openings extending through said blocks, one of said openings being enlarged and a clamp device passing through the openings in the two blocks, the faces of the respective blocks sliding upon each other with a motion of translation to vary the size of the opening between the blocks.

3. An adjustable wire lug including two solid blocks having overlapping pairs of contiguous inclined vertically offset parallel faces with interposed pockets forming a wire passage and a screw for drawing the blocks together, at least one of said blocks having an elongated perforation to permit said screw to shift from one portion to another of said elongated perforation as said blocks are drawn together, the faces of the respective blocks sliding upon each other without rotation to vary the size of the pocket opening between the blocks as they are drawn together.

4. An adjustable clamping connection for a

multiple stranded wire comprising a stationary jaw having an inclined guiding surface lower at one edge than another and a wire-supporting pocket open along the lower edge, a block mounted 5 to slide along said inclined surface and having a wire-gripping pocket open along its lower edge and coacting with the wire-supporting pocket to hold a wire between the walls of the pockets and clamping means for forcing the block to slide 10 along the inclined surface of the stationary jaw, said clamping means including a screw threaded member extending through the said inclined surface.

5. A wire terminal clamp comprising a base 15 member, a jaw member supported on the base member and having an inclined guiding surface and a wire-supporting pocket at the lower edge of the inclined surface, a clamping block supported and slideable on the inclined guiding surface 20 and having a wire clamping pocket coacting with a wire in the supporting pocket and a clamping bolt extending through the base member and through the inclined guiding surface of the jaw member and through the clamping block at one side of its pocket, the plane of the 25 guiding surface being inclined at a substantial angle relative to the axis of the clamping bolt.

6. An adjustable wire clamp comprising a substantially rectangular block having an upper and 30 a lower section, each section having a plurality of faces extending diagonally of said block, said

faces being parallel and vertically offset with respect to each other and being spaced by a non-parallel surface so as to form a pocket therebetween, the respective faces of each section being complementary to each other, said block 5 having a vertically extending passage passing through faces of an upper and a lower section, and bolt means extending through said passage.

7. An adjustable wire clamp comprising a substantially rectangular block composed of an upper and a lower section, a plurality of faces between said upper and lower sections extending substantially diagonally of said block and forming bearing surfaces for said sections, each face being complementary to an adjacent face on another section, each face on each section extending from an end of said section, each face of each section being parallel and vertically offset from another face of the same section, the offset faces being joined by a non-parallel surface 20 adapted to form a wire receiving pocket between said sections, said sections being slideable with respect to each other on said offset surfaces to vary the size of said pocket, said block having a bolt passage extending through one of said 25 faces of each of said sections, a part at least of said bolt passage being enlarged to permit adjustment of said sections, and a securing bolt extending through said passage.
